SHUTTLE CHANGING LOOM

Lewis S. Vose, Worcester, Mass., assignor to
 Crompton & Knowles Loom Works, Worcester,
 Mass., a corporation of Massachusetts

Application August 9, 1934, Serial No. 739,097

20 Claims. (Cl. 139—230)

This invention relates to improvements in shuttle changing double shuttle looms and it is the general object of the invention to prevent a shuttle smash if either active shuttle fails to be ejected from the loom on a shuttle changing operation.

Double shuttle looms operate with a lay having vertically aligned boxes and two shuttles which are picked simultaneously, one shuttle moving through the upper shed and the other shuttle through the lower shed to form a double fabric which is later split. In the type of loom to which my invention more particularly relates the lay comes to rest in rearward position and the old active shuttles are ejected from their shuttle boxes after which reserve shuttles from the magazines are inserted into the same boxes.

If, for any reason, either shuttle destined for ejection should fail to reach the magazine side of the loom there is a possibility that the magazine will insert fresh shuttles into the boxes which are empty due to non-arrival of the active shuttle, and on the first pick following the reserve and depleted shuttles will smash either in the shed or in the shuttle boxes. Failure of a shuttle to reach the magazine end of the lay on a changing beat may be due to faulty picking. It is an important object of my present invention to control the shuttle changing operations so that they cannot be completed until both depleted shuttles have been ejected and preferably though not necessarily have reached a given control point along the path of ejection. In this way definite assurance is given that the outgoing shuttles have actually been expelled from the lay before they are replaced by reserve fresh shuttles.

It is convenient to accomplish the ejection of the outgoing shuttles by raising the fronts of the boxes in which they are located and pushing the shuttles forwardly by means located behind the boxes. The removal of the box fronts is preferably though not necessarily accomplished in sequence so that one shuttle box is in condition for ejection of its shuttle before the other shuttle box. When the box fronts are consolidated into a single box front plate which is raised at the time of the shuttle change, this general result is accomplished by opening the front of the lower box while the front of the upper box is still closed by the plate as it rises. In this way I am enabled to eject the lower shuttle at a time when the box front positively holds the upper shuttle from being ejected, and consecutive ejections result.

It is a further object of my present invention to provide a control so constructed and operated

as to require two successive movements effected by consecutive ejections before permitting completion of a shuttle changing operation. In single shuttle shuttle-changing looms of the type specified a so-called receiver gate has been used which has a hook normally tending to prevent conveyance of a shuttle from the magazine to the lay and this hook is moved out of control position by the positive presence of a shuttle at the receiver gate. Such a control is inadequate for a double shuttle loom inasmuch as the ejection of one shuttle would operate such a control even though the other shuttle should remain in the shed or not be picked out of its box in the opposite side of the loom, in which case there would be a smash. As set forth hereinafter I provide a hook or the like to control the shuttle conveying levers but this hook is subjected to a control in addition to that heretofore given in that two shuttles must be present in order to move it to a position where shuttle changing can be completed. The two shuttles thus act jointly to control and permit changing, and when joint action does not occur there is no shuttle change.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an end elevation of a portion of a loom having my invention applied thereto, the parts being in position to start a shuttle changing operation,

Fig. 2 is a view similar to the upper central part of Fig. 1, but on an enlarged scale,

Fig. 3 is a diagrammatic perspective view showing the detector and magazine ends of the loom,

Fig. 4 is a diagrammatic perspective view showing the receiver gate and spent shuttle box,

Fig. 5 is a plan view taken in the direction of arrow 5, Fig. 2, showing the lower ejector,

Figs. 6, 7 and 8 are detail diagrammatic side elevations showing successive positions of the receiver gate, and

Figs. 9, 10 and 11 are diagrammatic views showing the positions of the conveyor levers and control hook for the positions corresponding to Figs. 6, 7 and 8, respectively.

Referring particularly to Figs. 1 and 2, the loom frame 20 has a lay 21 pivoted as at 22 and having upper and lower shuttle boxes 23 and 24, respectively. The lay end 25 secured to the lay has pivoted to the upper end thereof a

lever 26 the forward or right end of which as viewed in Fig. 1 is pivoted as at 27 to a box front structure 28. A substantially vertical link 29 is operatively connected to lever 26 and is attached to an arm 30 pivoted to the lay and connected to an operating rod 31. The latter is connected to the forward end of a cam lever 32 pivoted as at 33 to the loom frame and arranged for operative relation with respect to a cam 34. The cam is secured to a so-called change shaft 35 which is normally stationary but is set into rotation whenever a shuttle changing operation is to take place. A handle 36 may extend upwardly from lever 26 a link 37 connecting link 29 and lever 26 and affords means by which the box plate can be raised manually.

Pivoted as at 40 to the upper part of the lay end is an ejector lever 41 having a screw 42 to engage a block 43 on the forward end of a link 44 the rear end of which is pivoted as at 45 to the lay end. A short link 46 is interposed between the block and the box structure 28 and swings around pivot 27. Extending downwardly from the lever 41 is an arm 47 to the lower end of which is adjustably secured an upper ejector 48 arranged to pass through the back 49 of the lay end to strike shuttle S and move it out of the upper box 23. A spring 50 between lever 26 and the lay end holds said lever and the box front normally in down position.

As shown particularly in Fig. 1 there are front and back reserve shuttle magazines M and M', respectively, which have conveyors 55 and 56, respectively, arranged to move reserve shuttles from the magazines toward the lay. The conveyors 55 and 56 are secured to levers 57 and 58, respectively, both of which move about a fixed pivot 59 carried by the loom frame. Lever 57 has a roll 60 to coat with a relatively large cam 61 fast on the change shaft 35, while lever 58 has a roll 62 to engage a somewhat smaller but similar cam 63.

As shown in Fig. 3 I have set forth upper and lower electrical weft detectors 65 and 66, respectively, which operate by known mechanism to start rotation of shaft 35. This control may if desired be similar to that found in my co-pending application Serial No. 603,051. An apron 68 is attached to the lay and extends forwardly and downwardly between the back of a shuttle catcher box 69 and a guide rod 70 thereon.

In the operation of the matter thus far described the upper and lower shuttles S and S', respectively, will be picked back and forth together through upper and lower warp sheds W and W', respectively, the shuttles travelling together to produce a double fabric as indicated in Fig. 2. When the shuttles are on the detector end of the loom they coat with the detectors 65 and 66, and should either of these detectors indicate exhaustion of weft, shaft 35 will be set in rotation and the loom will be brought to rest with the lay in a rear position such as indicated in Fig. 1. As the shaft 35 rotates rod 31 will be depressed by rise 37^a of cam 34 to rock lever 26 in a counterclockwise direction as viewed in Fig. 1, thus raising the front box plate structure 28. The link or rod 44 serves in this connection to give the plate 28 a substantially parallel motion, an arm of the lever 26 and said rod 44 acting substantially as parallel links for the purpose.

During the upward motion of the plate 28 block 43 will engage the screw 42 to rock lever 41 about its axis and move ejector finger 48 forwardly or to the right to engage the upper shuttle

which is in shuttle box 23. A spring 38 returns lever 41 to normal position after it is rocked by the block.

Rotation of shaft 35 also causes movement of the conveyor levers 57 and 58, these levers each having a slight forward motion to release the bottom shuttles from the magazines M and M'. this result being accomplished by the rising surface 75 on cam 61, for instance, and a similar surface on cam 62. Dwells 77 on these cams hold the conveyors forward while the active shuttles are ejected. Continued rotation of shaft 35 later in the cycle results in rearward motion of the conveyor levers under the influence of their springs 76, the rearward motion being permitted by surfaces 64 of the cams as they rotate. The new shuttles are thus carried from the magazine toward the shuttle boxes 23 and 24 and, assuming for the moment that the shuttles S and S' have been ejected, the incoming shuttles are placed in the boxes on the lay. The box plate 28 has been held up by dwell 39 during this time, but now by reason of incline 77 descends and mechanism not shown but well understood and controlled from the shaft 35 starts the loom running again.

The matter thus far described of itself forms no part of my present invention and may be the same as structures set forth in the following patents, Cowan No. 1,906,544, Jackson 1,434,211 and Jackson, No. 1,133,802. The effect of operation of the loom is to replace the two active shuttles with two fresh shuttles on the same shuttle changing operation of the loom, preferably while the loom is temporarily stopped, and if desired this shuttle changing operation may be initiated by the detectors shown in Fig. 3, although I do not wish to be limited to this mode of controlling shaft 35.

As previously stated if for any reason either of the active shuttles should fail to move out of the loom a smash will result upon the first pick following resumption of loom operation and I aim to prevent such a smash by preventing or revoking transfer of the fresh shuttles. The particular means for accomplishing this result as set forth hereinafter, contemplates arrival of the ejected shuttles at a control mechanism in sequence, or consecutively.

The mechanism for discharging one shuttle 50 ahead of the other, as shown in Fig. 1, comprises a cam lever 80 moving about pivot 33 and contacting with a cam 81 fast on shaft 35 and having a point 82. Extending upwardly from this lever is a rod 83 which as shown on larger scale in Fig. 2 is connected to a bell crank lever 84 pivoted as at 85 to the lay 10. The lower arm 86 of this lever is operatively connected to a shuttle pusher 87 indicated in detail in Fig. 5. The body of this pusher may be square and moves through similarly formed guide bearings 88 to prevent rotation and the forward end has a head 89 with three fingers 90 to engage the lower shuttle. The rod has an adjustable collar 91 which is driven by the arm 86 of the bell crank lever.

Reference to Fig. 1 shows that the point 82 of cam 81 becomes operative to depress lever 80 early in the rotation of shaft 35 and completes the ejection of the lower shuttle while cam lever 32 is still rising on incline 37^a. By this relation the pusher head 89 engages the lower shuttle and moves the same forwardly out of box 24 and on to apron 68 before cam 34 lifts plate 28 high enough to release the upper shuttle S in box 23. 75

Operation of the previously described pusher finger 48 comes later in the sequence of operations, since it depends upon up motion of box plate 28 after the latter is clear of the top shuttle. The upper shuttle is therefore ejected after the lower shuttle has been started on its downward path toward the box 69. From this it will be seen that upward movement of box structure 28 is timed to prevent discharge of the upper shuttle until after the lower shuttle is out of its box, a relation which is obtained by the setting of cams 34 and 81.

By that part of my invention already described it is apparent that the active shuttles are discharged from the lay consecutively or in sequence so that there is an appreciable interval of time lapsing between the ejection of the lower and upper shuttles. I do not wish to be limited to the specific means shown for ejecting the active shuttles, since the important part of this form of my invention is the consecutive arrival of the outgoing shuttles at a definite point regardless of the manner of their ejection or control subsequent to ejection.

In carrying my invention into further effect I provide means for preventing rearward motion of the conveyors of the shuttles of the magazines unless both shuttles are ejected from the boxes 23 and 24. This part of my invention is set forth particularly in Figs. 4, and 6 to 11. The box or receiver for spent shuttles has vertical side plates 95 across which extends a shaft 96, as shown in Fig. 4, rotatable in bearings 97 on the box. That end of the shaft which is near the conveyor levers has loosely pivoted thereon a controller 98 the rear of which is provided with a hook 99 adapted for entry into a notch 100 located as set forth herein in conveyor lever 57.

A counter-weight 101 of the controller acts to hold the hook up against the under side 102 of the conveyor lever 57. Secured to the shaft 96 is a short vane 103 and a longer vane 104 spaced angularly therefrom around shaft 96, and these vanes are counter-weighted by a third vane 105. A friction strap 106 anchored as at 107 on the box and tensioned by a spring 108 extends around a part of the shaft 96 to dampen vibration of said shaft and retard motion of the vanes. Lever 57 has a stop pin 110, Figs. 1 and 9, extending laterally therefrom into restraining relation with respect to the other conveyor lever 58 as set forth particularly in Fig. 9, so that if for any reason rearward motion of 57 is prevented the stop pin will also arrest rearward motion of the other conveyor lever.

A clutch element 115 is secured to shaft 96 by a set screw 116 in adjusted angular position and has a tooth 117 to engage a second tooth 118 formed as part of the controller 98. These teeth are adapted for engagement with each other under conditions to be described but are normally spaced so that the controller is not affected by tooth 117 but is held in normal position only by its own counter-weight 101. A collar 120 confines the controller between itself and clutch part 115.

As already described the first part of the shuttle changing operation results in forward motion of the conveyor levers to take shuttles from the magazines, and this moves notch 100 to a position where hook 99 will tend to enter under action of the counter-weight 101. When the lever 57 is forward the hook and notch will be related as shown in dotted lines in Fig. 6, and the lever will be held against rearward motion. The shut-

ties which are ejected from the shuttle boxes have their inner ends supported temporarily by a pin 125 which extends forwardly from the lay, as shown in Fig. 4.

With the parts in this position the first or lower shuttle moves down the apron toward the box and strikes the short vane 103 to give shaft 96 a partial rotation so that the vanes move from the position shown in full lines Fig. 6 to the position of Fig. 7. Vane 104, which was previously out of the path of the shuttles, is now positioned for engagement with the second or upper shuttle. While the vanes move to the position shown in Fig. 7 the tooth 117 moves up close to tooth 118 of the controller, but this motion is not sufficient to move the hook 99 out of the notch and the parts will remain in the position shown in Fig. 7 with the hook or controller in restraining relation with respect to the conveyor lever 57.

When the second shuttle S reaches the receiver gate it will strike vane 104, turning the latter to the position of Fig. 8 and giving shaft 96 an additional rocking motion which moves tooth 117 against tooth 118 and rocks the controller to the position shown in Fig. 8 where the hook is out of the notch. The parts are so related that counter-weight 101 strikes and is held by surface 102 of lever 57 before the second shuttle can fall completely into the receiver box, this shuttle maintaining the hook out of the notch until the lever 57 moves far enough rearwardly to place the notch out of line with the hook.

While the friction strap 106 is not necessary, yet I find it convenient as it tends to hold the setting given by the first shuttle until the second shuttle arrives. It is not necessary to keep the vanes in the position shown in Fig. 8 after the notch 100 has moved rearwardly away from the hook 99 and at some later time hook 99 will return to the position shown in Fig. 6 where it will no longer be capable of exerting control over the conveyor levers. It is to be remembered that the normal position of the lever 57 when not changing shuttles is with notch 100 behind the hook.

It will be apparent that if either shuttle should fail to reach the receiver gate or vanes, the latter will not be given the two part motion which they require before permitting the conveyor levers to complete the changing operation which they start. Likewise, if both shuttles should fail to reach the vanes due to a defect of the ejectors, or failure to reach the boxes 23 and 24, the hook will remain in controlling position and arrest shuttle change.

The consecutive arrival is provided for by the successive ejection at the shuttle boxes, but as already stated, so far as the controller for the conveyor levers is concerned it is immaterial what means is provided to insure successive arrival of the shuttles at the receiver gate and I do not wish to be limited to the form of shuttle ejector shown herein. While I have shown a loom of the type which stops to change shuttles, yet certain features of my invention are not dependent upon stopping and I do not wish to be limited to that particular type of shuttle changing loom.

From the foregoing it will be seen that I have provided means which will prevent or revoke a shuttle changing operation unless both shuttles in boxes 23 and 24 are rejected, and preferably reach a definite prescribed point in the path of their rejection from the lay. It will also be seen that the control is accomplished through two

movements of shaft 96. It will also be seen that the box front structure 28 is so controlled as to assist in the consecutive ejection of the active shuttles, this structure permitting discharge of the lower shuttle at a time when the upper shuttle is positively restrained from being ejected.

Having thus described my invention it will be seen that changes and modifications may be made therein by those skilled in the art without departing from the spirit and scope of the invention and I do not wish to be limited to the details herein disclosed, but what I claim is:

1. In a shuttle changing double shuttle loom having two active shuttles which are picked together, means to eject both active shuttles on the same shuttle changing operation of the loom, mechanism to place two reserve shuttles into action to replace the ejected shuttles, and means to prevent operation of the mechanism if either active shuttle fails to be ejected.
2. In a shuttle changing double shuttle loom having two active shuttles which are picked together, means to eject both active shuttles on the same shuttle changing operation of the loom, mechanism to place two reserve shuttles into action to replace the ejected shuttles, and control means for the mechanism normally effective to prevent operation of the mechanism and rendered ineffective to prevent operation of the mechanism
3. In a shuttle changing double shuttle loom having two shuttle boxes from which active depleted shuttles are ejected and into which reserve shuttles are placed, means to eject both shuttles from the boxes on the same shuttle changing operation and to direct them along a given path, mechanism to move a reserve shuttle into each box, and means to prevent the mechanism from moving the reserve shuttles into the boxes unless the ejected shuttles have reached predetermined points along said path.
4. In a shuttle changing double shuttle loom having two shuttle boxes from which active shuttles are ejected and into which reserve shuttles are placed, means to eject a shuttle from each of the boxes during the same shuttle changing operation of the loom, mechanism normally operative thereafter on the same shuttle changing operation of the loom to place a reserve shuttle in each shuttle box, and a controller for the mechanism having a tendency to prevent operation of the latter and movable by the combined action of both ejected shuttles to overcome said tendency and permit said mechanism to operate.
5. In a shuttle changing double shuttle loom having two shuttle boxes from which active shuttles are ejected and into which reserve shuttles are placed, means to eject both shuttles from the shuttle boxes during the same shuttle changing operation, mechanism thereafter normally effective on the same shuttle changing operation of the loom to place a reserve shuttle in each shuttle box, a controller normally tending to prevent operation of the mechanism, and preventer means dependent upon presence of both ejected active shuttles at a given point to move said controller out of normal position thereby permitting the mechanism to operate, presence of but one shuttle at said point being ineffective to move the controller out of normal position.
6. In a shuttle changing double shuttle loom having two shuttle boxes from which active

shuttles are ejected and into which reserve shuttles are placed, a pair of shuttle ejectors, one for each shuttle box, each to eject a shuttle from a shuttle box during the same shuttle changing operation of the loom, a plurality of reserve shuttles, transfer mechanism to move two shuttles from the plurality to the boxes, one for each box, and a controller for said transfer mechanism in a condition normally tending to prevent operation thereof and movable by the combined presence of both ejected shuttles at given points out of said condition.

7. In a shuttle changing double shuttle loom operating with two active shuttles both of which are picked on each beat of the loom, means to eject both shuttles from the loom on the same shuttle changing operation when depletion of weft occurs in either shuttle, mechanism normally operative thereafter to start to move two reserve shuttles into active position to replace the previously active pair of shuttles, and control means for the mechanism capable of interrupting operation thereof and rendered incapable of interrupting said operation by presence of both the previously active shuttles at a given point outside the loom.

8. In a shuttle changing double shuttle loom having two active shuttles which are picked together, means to eject both active shuttles on the same shuttle changing operation of the loom, mechanism to place two reserve shuttles into action to replace the ejected shuttles, and means dependent upon successive arrival of the ejected shuttles at a given point outside the loom to allow operation of the mechanism and operation to prevent operation if either active shuttle fails to be ejected.

9. In a shuttle changing double shuttle loom having two shuttle boxes from which active shuttles are ejected and into which reserve shuttles are placed, means to eject the active shuttles from the shuttle boxes in succession on the same shuttle changing operation, mechanism normally operative thereafter to replace the active ejected shuttles with reserve shuttles, a controller normally tending to prevent operation of the mechanism, and means dependent upon the successive arrival of the ejected shuttles at a given point to move the controller out of preventing position relatively to the mechanism.

10. In a shuttle changing double shuttle loom having two shuttle boxes from which active shuttles are ejected and into which reserve shuttles are placed, means to eject the active shuttles in succession during the same shuttle changing operation of the loom, mechanism normally operative thereafter to place reserve shuttles in the shuttle boxes, a preventer normally tending to prevent operation of the mechanism, and control means for the preventer operative by the successive arrival of both ejected shuttles at a given point to move the preventer out of preventing relation with respect to the mechanism.

11. In a shuttle changing double shuttle loom having two shuttle boxes from which active shuttles are ejected and into which reserve shuttles are placed, a front plate common to both shuttle boxes, means to move said plate in a vertical direction relatively to the boxes at the time of the shuttle change operation, said plate exposing the shuttle of one box before exposing the shuttle of the other box, means to eject the shuttles from the shuttle boxes in sequence, and mechanism dependent upon successive arrivals of the

ejected shuttles at a given point to move reserve shuttles into the shuttle boxes.

12. In a shuttle changing double shuttle loom operating with two active shuttles, means to eject the shuttles successively on the same shuttle changing operation of the loom, and mechanism dependent upon successive arrivals of the shuttles at a given point outside the loom to move reserve shuttles into active position to replace the ejected shuttles.

13. In a shuttle changing double shuttle loom, a pair of shuttle boxes each to receive an active shuttle preparatory to a shuttle changing operation, means to eject the active shuttles from the boxes along given paths, reserve shuttles, mechanism to move a reserve shuttle into each shuttle box during a shuttle changing operation, and means to prevent the completion of a shuttle changing operation by the mechanism unless both active ejected shuttles reach predetermined points along their paths.

14. In a shuttle changing double shuttle loom, a pair of shuttle boxes, mechanism to move a reserve shuttle into each shuttle box during the same shuttle changing operation, ejector means to move the active shuttles from the boxes, and means to prevent the completion of the operation of the mechanism unless both active shuttles are moved by the ejector means to predetermined positions out of the loom.

15. In a shuttle changing double shuttle loom operating with two active shuttles, means to remove said shuttles from action, mechanism to replace said shuttles with reserve shuttles on the same shuttle changing operation of the loom, and means to prevent operation of the mechanism unless both active shuttles are removed from action.

16. In a shuttle changing double shuttle loom operating with two active shuttles, means to eject the shuttles successively on the same shuttle changing operation of the loom, and mechanism dependent upon successive passage of the shuttles by a given point to replace said shuttles with fresh reserve shuttles.

17. In a shuttle changing double shuttle loom

operating with two active shuttles, means to eject the shuttles on the same shuttle changing operation of the loom, mechanism to replace the ejected shuttles with fresh reserve shuttles, and two controllers for the mechanism, one to be operatively related to one ejected shuttle and the other to be operatively related to the other ejected shuttle, said mechanism being dependent for its operation upon the operative relation of each controller with its respective ejected shuttle.

18. In a shuttle changing double shuttle loom operating with two active shuttles, means to eject both shuttles on the same shuttle changing operation of the loom, shuttle changing mechanism to replace the ejected shuttles with fresh reserve shuttles, and two controllers for the changing mechanism, one to be operatively related to each shuttle, operation of the changing mechanism being dependent upon operative relation of each controller with an ejected shuttle.

19. In a shuttle changing double shuttle loom operating with two active shuttles, means to eject both shuttles on the same shuttle changing operation of the loom, shuttle changing mechanism to replace the ejected shuttles with fresh reserve shuttles, and controller means to be given two operative movements, one movement by each ejected shuttle, operation of the shuttle changing mechanism being dependent upon the two operative movements by the controller means.

20. In a shuttle changing double shuttle loom operating with two active shuttles, means to initiate a shuttle changing operation of the loom with respect to both active shuttles, ejector mechanism controlled by the means to eject both active shuttles on the same shuttle changing operation of the loom, shuttle changing mechanism controlled by the means to thereafter replace the ejected active shuttles with two reserve shuttles, and control means exerting a preventing control over the shuttle changing mechanism and rendered incapable of exerting said preventing control only upon the ejection of both active shuttles.

LEWIS S. VOSE.
